PACKING CASE FOR HATS

Filed May 17, 1926

Patented Mar. 27, 1928.

1,663,928

UNITED STATES PATENT OFFICE.

ERNEST A. WALTHER, OF DANBURY, CONNECTICUT.

PACKING CASE FOR HATS.

Application filed May 17, 1926. Serial No. 109,504.

This invention relates to packing cases or holders for hats, and has for an object to provide such a case which for the same size of outer container will hold a much larger 5 number of hats than can be packed in the cases now generally used.

It is also an object of the invention to provide a case in which there is no weight 10 on any hat from any other hat or element located above the same, and therefore, there will be nothing to mar the surfaces of the 15 hat while it is packed in the case.

It is a further object of the invention to provide means for holding the hats in the 20 proper position which will also strengthen and support the outer container or carton so that the completely packed case or carton will be stronger and will stand more rough handling in transit.

25 It is a still further object of the invention to provide a packing case the use of which will greatly reduce the cost of packing and shipping hats over the means now generally in use.

With the foregoing and other objects in view, I have devised the construction illustrated in the accompanying drawing forming a part of this specification, similar reference characters being employed throughout 30 the various figures to indicate corresponding elements. In this drawing,

Fig. 1 is a partial plan view and partial horizontal section of my improved packing case or carton showing the frames in position but with the hats omitted.

Fig. 2 is a vertical section through the same substantially on line 2—2 of Fig. 1, one column of the supporting frames being shown in section and most of those in the 40 other two columns being shown in elevation, while the hats are shown in elevation.

Fig. 3 is a side elevation of one of the frames.

Fig. 4 is a bottom plan view thereof.

45 Fig. 5 is a detail of one corner of the blank for forming the frame.

Fig. 6 is a vertical section through the frame substantially on line 6—6 of Fig. 4.

Fig. 7 is a view similar to Fig. 2 on an 50 enlarged scale showing only a portion of a case and also showing a slightly different construction for the frames.

Fig. 8 is a side elevation of one side of the frame shown in Fig. 7, and

55 Fig. 9 is a detail of one corner of the blank forming the frame shown in Fig. 7.

As hats are now generally packed for shipment and storage they are placed in a substantially round light paste board box, a hat being placed at the bottom of the box, 60 an upright paste board ring being placed on the brim of the hat, the next upper hat being placed on top of this ring, another and similar ring being placed on the top of the brim of the second hat and so on. 65 This system has numerous objections. In the first place only a small number of hats may be placed in a single box and as the rings supporting the hats are placed on the brim of the next lower hat the nap on the 70 surface of the hat is pressed down by the edges of the rings marring the surfaces of the hats, and furthermore, the weight of all rings and hats above a given hat are supported on the brim of this hat. These round 75 boxes also require a great deal of room in shipping and storing as they are made up complete in the factory.

To obviate these objections I have devised the construction and arrangement shown in 80 the accompanying drawing. In this drawing 10 indicates the outer container generally known as a carton which is rectangular in cross section and is usually made of corrugated paper board. It is closed at the top 85 by four flaps or cover sections 11 and 12, the sections 11 being connected to the top of the end walls and foldable inwardly over the top while the sections 12 are connected to the tops of the side walls and foldable over 90 the sections 11. In the present practice the round boxes containing the hats mentioned above are placed in this container or carton and shipped therein, there usually being six 95 of these boxes placed in one carton.

In my method of packing, however, I do away entirely with the round boxes and pack the hats in the carton. For this purpose I provide a plurality of frames 13 preferably made of a suitable cardboard. In the form shown in Figs. 1 to 6 a blank is cut from a piece of cardboard leaving notches 14 at the corners thereof and also forming a central oblong opening 15. The frame is formed by bending downwardly the side 105 walls 16 about the dotted lines 17 at the edges of the top walls thus leaving a rectangular top wall 18 and providing upright downwardly extending side walls 16. The blank may be scored along the dotted lines 110 to facilitate this bending. These side walls are secured together by any suitable means

such as small strips of paper 19 pasted over the meeting ends of two adjacent side walls. This construction forms a rigid frame of great strength and stiffness considering the material of which it is constructed. In cutting the blank the edges 20 of the notch 14 which form the ends of the side walls are inclined somewhat, as shown in Fig. 5, so that the lower free edges of the side walls are shorter than the top edges, and thus when the side walls are secured together in the upright position the frame is smaller at its lower side than at its upper side, that is, the distance between the lower edges of opposite side walls is less than the corresponding width of the top wall. This is so that when the frames are placed in superposed relation the lower edges of the side walls will be sure to rest upon the top wall of the next lower frame with no danger of their sliding off at one side and falling down out of position.

In packing the hats, the first hat 21 is placed on the bottom of the outer container or carton 10, then a frame 13 is placed over this hat with the crown if high enough passing through the opening 15 and the lower edges of the side walls 16 of the frame resting on the bottom wall of the carton. The next hat is then placed with its brim resting and supported on the top wall of this frame, and then a second frame is placed about the second hat with the lower edges of its side walls resting on the top wall of the first frame, and so on until the column is completed. It will be seen that in the present arrangement there are six columns of these frames in a single carton each frame containing a hat, and the frames are of such a size as to completely fill the inside of the outer container or carton and just snugly fit the same. When all of the frames have been placed in the carton, spacers 22 are seated on the top frames and extend between these frames and the top wall of the carton to prevent their shaking around and getting out of position during transit. These spacers are usually strips of corrugated paper board the same as the carton.

In Figs. 7, 8 and 9 I have shown a slightly different construction for bringing in the lower edges of the side walls or making smaller the lower end of the frame. In this construction the edges 23 of the notches cut at the corners of the blank for the frame 24 are made substantially straight for a portion of their length and then they are inclined by cutting away a portion of the side walls, as shown at 25, Fig. 9. Thus when the side walls 26 are folded about the dotted lines 17 the upper portion of the side walls are substantially vertical, as shown in Figs. 7 and 8, but the lower portions 27 thereof below the point 28 are drawn inwardly when the paper strip 19 is applied thereto,

as indicated in Fig. 7. This arrangement gives the same effect as the inclined side walls in the first form. That is, the lower part of the frame is smaller than the top wall to insure that the lower edges of the side walls of each frame will rest on the top wall of the next lower frame. This construction, however, has the advantage that the vertical upper portion of the side walls bears against the side of the carton and the side wall of the next adjacent frame in the same layer and gives a better bearing surface therewith than in the first form shown in Figs. 1 to 6. Otherwise the function and operation are practically the same.

From the foregoing description it will be apparent that there is no weight on any hat as each frame is supported directly on the next lower frame and the bottom frame is supported on the bottom of the carton. The construction of the frame gives it considerable strength and stiffness, and as the frames fit snugly against each other and engage the sides of the carton they add considerable strength and stiffness to this carton so that it will stand considerable more handling in use and will be less liable to be crushed. Also each hat is supported entirely independently of any other hat and in such a way that there is little danger of marring the surface thereof. Still further a carton of a given size will carry a great many more hats with this construction and arrangement than where the round or oval boxes now generally employed are used. The frames, furthermore, can be stored in much less space because they may be shipped and stored flat as shown in Figs. 5 and 9, and then the side walls may be bent to the upright position and secured by the strips 19 as the frames are required for use. They thus require much less space for storing and shipping than do the round or oval boxes.

Having thus set forth the nature of my invention, what I claim is:

1. A holder for hats comprising an outer carton and a plurality of superposed frames for holding the hats, each frame having a horizontal top wall adapted to support the brim of a hat, said wall being provided with an opening for passage of a hat crown and also having downwardly extending side walls on the sides thereof resting directly on the top wall of the next lower frame whereby each hat is supported independently of the weight of the other hats.

2. A packing case for hats comprising an outer carton and a plurality of superposed frames for holding the hats, each frame having a horizontal top wall on which the brim of a hat may be supported and which wall is provided with an opening for the crown of the hat on the next lower frame, and each frame also having downwardly extending upright side walls at its periphery resting

directly on the top wall of the next lower frame to support the frame whereby each hat is supported independently of the weight of the other hats.

3. A packing case for hats comprising an outer rectangular container and a plurality of superposed frames, each frame having a rectangular top wall on which the brim of a hat may be supported and which is provided with an opening for the crown of the hat on the next lower frame, said frames being each provided with upright side walls extending downwardly from the side edges of the top wall resting directly on the top wall of the next lower frame and supported thereby whereby each hat is supported independently of the weight of the other hats.

4. A packing case for hats comprising an outer rectangular carton and a plurality of superposed frames each frame having a rectangular top wall on which the brim of a hat may be supported and also provided with an opening for the crown of the hat on the next lower frame, said frames also having upright side walls extending downwardly

from the edges of said top wall and resting at their lower edges on the top of the next lower frame whereby each hat is supported independently of the weight of the other hats, the distance between said lower edges 30 being less than the width of the top wall.

5. A packing case for hats comprising an outer container and a plurality of superposed pasteboard frames, there being a frame for each hat and comprising a rectangular horizontal top wall on which the brim of a hat may be placed with the hat in its normal upright position, said wall being provided with an opening for the crown of the hat on the next lower frame, 40 each frame also having downwardly extending upright side walls connected at the four edges of the top wall and resting at their lower edges on the top wall of the next lower frame and supported thereby whereby each 45 hat is supported independently of the weight of the other hats.

In testimony whereof I affix my signature.

ERNEST A. WALTHER.
